UNITED STATES PATENT OFFICE.

WILLIAM H. GOLDSON, OF OAKLAND, CALIFORNIA.

BOAT.

1,412,517.

Specification of Letters Patent. Patented Apr. 11, 1922.

Application filed September 26, 1919. Serial No. 326,486.

To all whom it may concern:

Be it known that I, WILLIAM H. GOLDSON, a citizen of the United States of America, a resident of Oakland, in the county of Alameda, State of California, have invented 5 certain new and useful improvements in Boats, of which the following is a full, clear, and exact description, reference being had to the accompanying drawings, forming a 10 part of this specification.

My invention relates to improvements in boats. Generally stated, an object of the invention is to provide means whereby the power transmitted from the propellers is 15 most effectively utilized. Another object is to produce a strong and durable tunnel structure wherein the propellers are mounted in such a manner that the boat can be effectively driven either in shallow water 20 or deep water.

In the preferred form of the invention, the boat is provided with an overhanging false stern, and propeller tunnels are formed under this false stern. A transverse inlet 25 is formed at the forward ends of the tunnels to provide for the admission of water to all of the tunnels, and the water drawn through this inlet passes to the propellers, which preferably lie in the forward ends 30 of the tunnels.

Another object is to produce a tunnel structure of this kind in which the sides of the tunnels are firmly secured and rigidly braced to resist the lateral pressure of the 35 streams of water discharged from the propellers.

With the foregoing and other objects in view, the invention comprises the novel construction, combination and arrangement of 40 parts hereinafter more specifically described and illustrated in the accompanying drawings, wherein is shown the preferred embodiment of the invention. However, it is to be understood that the invention comprehends 45 changes, variations and modifications which come within the scope of the claims hereunto appended.

Fig. I is a side elevation of the rear portion of a boat constructed in accordance 50 with this invention.

Fig. II is a longitudinal section taken through the rear portion of the boat.

Fig. III is an inverted plan view of the structure shown by Figs. I and II.

Fig. IV is a top or plan view, showing the elements at the rear end of the boat.

Fig. V is an enlarged fragmentary vertical section showing a means for adjusting one of the deflector wings.

Fig. VI is an enlarged fragmentary section showing the means for locking the adjustable deflector wing. 60

Fig. VII is a fragmentary view, illustrating the rear end portion of one of the deflector wings. 65

Fig. VIII is a vertical section showing a portion of one of the tunnel walls and portions of deflector wings closely fitted to the tunnel wall.

Fig. IX is a detail view, showing one of 70 the packing strips at a margin of the inlet door.

Fig. X is a fragmentary vertical section taken through the inlet ends of the propeller tunnels. 75

Fig. XI is a view similar to Fig. X, showing the adjustable deflector wings in the tunnels.

1 designates the hull of a boat provided with a stern A (Figs. I, II and III) and 80 an overhanging false stern A'. 2 designates the floor, or deck, forming the bottom of the overhanging stern. Longitudinal side wall members 3 extend downwardly from the sides of the overhanging stern. A series 85 of longitudinal partitions 3' (Figs. II and III) are located between and arranged parallel with the side wall members 3 to provide a series of open-bottom propeller tunnels B under the entire bottom of the overhanging false stern. The side walls 3 and partitions 3' are rigidly secured to the false stern, and they are braced, as will be hereafter described, to produce a very strong tunnel structure. 90

Propellers 4 are located in the forward ends of the tunnels at points adjacent to the stern A, said propellers being fixed to rotatable shafts 5 passing through the stern A and adapted to be driven by a motor M, 100 shown by dotted lines in Figs. I and II. The forward ends of the wall members 3 and partitions 3' are separated from the stern A to provide a transverse inlet passageway C (Figs. II and III) communicating with all of the tunnels B. This inlet passageway preferably extends entirely across the boat, and its ends may be closed by adjustable doors 6 at opposite sides of the boat. The margins of each door 6 are 110 preferably provided with yielding strips of packing 7 (Fig. IX), adapted to engage a

side of the boat, and a yielding strip of packing 8 may be mounted in the side of the boat, as shown by dotted lines in Fig. I. The ends of each door 6 are mounted in 5 vertical guides 9 (Figs. I and III). The means for adjusting the doors 6 (Figs. I, II and III) comprises threaded rods 10, screwed into brackets 11 and having their lower ends secured to said doors. Each 10 door 6 may be provided with a socket 12 adapted to receive a head 13 (Fig. I) on the lower end of threaded rod 10.

Inclined deflector wings 14 extend downwardly from the forward ends of the tunnels 15 B to the rear ends thereof, so as to form inclined top walls for said tunnels, the longitudinal edges of said wings being provided with yielding strips of packing 15, secured by strips of metal 16, as shown in 20 Figs. VII and VIII, and adapted to engage the side walls of the tunnels. The upper end of each deflector wing 14 is pivotally supported by a hinge 17 (Fig. II), and to prevent leakage at this point a strip of yielding packing 18, preferably rubber, is interposed between the hinge and a floor board 19. 25 20 designates screws (Fig. II) whereby the floor board 19 is removably secured to the boat.

30 The means for adjusting the deflector wings 14 is shown in Figs. II, IV and V. A vertical adjusting screw 21 is located over each wing 14 and arranged in a column 22, provided with a head 23, the latter being threaded to receive the adjusting screw. Each adjusting screw 21 is connected to a 35 rod 24 by means of a universal joint 25. 26 26 designates a ball and socket joint (Fig. V), whereby the lower end of rod 24 is connected to deflector wing 14. Each adjusting screw 21 is provided with an operating 40 wheel 27, which may be rotated to raise and lower the screw in the head 23, thereby raising and lowering the deflector wing 14 45 to which the screw is connected.

To illustrate a suitable means for locking the deflector wings (Figs. II, IV, VI and VII), I have shown teeth 28 on the rear edges of the longitudinal tunnel walls, and 50 flat springs 29 adapted to interlock with these teeth. Each spring 29 (Figs. VI and VII) may be secured to the rear edge of a wing 14 by means of fastening devices 30, leaving the projecting ends of the spring 55 free to be forced away from the deflector wing. To lock a deflector wing, the free ends of spring 29 interlock with the teeth 28 (Fig. VI), and the wing may be unlocked by bending the end portions of spring 60 29 to release them from the teeth 28. The means for bending the springs 29 to unlock the deflector wings comprises cams 31 secured to shafts 32. Each cam 31 engages an end portion of a spring 29, and by 65 referring to Fig. VII it will be seen that the

cams are adapted to force the end portions of the spring away from the deflector wing, so as to release the spring from the teeth 28 shown in Fig. VI. The means for operating the cam shafts 32 comprises vertical 70 shafts 33 loosely mounted in hollow columns 34, the upper end of each shaft 33 being provided with an arm 35, to which an operating bar 36 is pivotally connected. The lower end of each shaft 33 is connected by means of a universal joint 37 (Fig. VI) to a shaft 32. There are two cams 31 and two operating shafts 33 for each of the deflector wings, and the shafts 33 associated with the same wing are connected together by means of 80 arms 35 and connecting bar 36. The several deflector wings 14 can therefore be unlocked independently of each other, and they can also be adjusted independently of each other. 85

Suction chambers 38 (Figs. II, III and X) are located over the propellers 4, each of said chambers having an open lower end large enough to receive a column of water which overlies the entire propeller. The upper portion of each suction chamber is provided with a suction pipe 39 (Fig. II) adapted to be connected to a pump (not shown), whereby water may be drawn into the suction chamber. When the boat is operated in shallow water, a column of water may be maintained in each suction chamber 38, and this would enable the propellers to more effectively perform their functions in shallow water. When the boat is heavily 100 loaded and operated in deep water, the inlet doors 6 may be opened and the deflector wings 14 may be elevated to lie entirely within the upper portions of the tunnels. In very shallow water the inlet doors 6 may 105 be adjusted to their lowermost positions, as shown in the drawings, but they are preferably elevated as high as possible without withdrawing their lower margins from the water. An adjustment of this kind would 110 allow the water to freely pass under the lower margins of the inlet doors, and when discharged from the propellers, the streams of water would strike the inclined deflector wings 14. In shallow water the lower margins of these inclined wings would be submerged, and if desired a column of water 115 could be maintained in each suction chamber 38.

40 designates rudders alined with and extending rearwardly from the longitudinal partitions 3' (Figs. II and III), said rudders being fixed to vertical shafts 41. By locating the rudders at the rear ends of partitions 3', as herein shown, the streams of water discharged from the tunnels will forcibly strike the rudders, thereby causing the body to respond quickly to an adjustment of the steering mechanism. 120

The rudder shafts 41 are free to move 130

vertically in stuffing boxes 42, and the lower edge of each rudder is inclined upwardly, as shown at 43 in Figs. I and II, so as to enable the rudder to be forced upwardly when its 5 forward end strikes an obstruction. This will enable the rudders to pass freely over obstructions without injury to the steering mechanism.

To obtain the best results under different 10 operating conditions, the rudders can be adjusted vertically through the medium of adjusting devices shown in Figs. II and IV. A collar 44 is fixed to each rudder shaft, and a collar 45 is loosely mounted on said shaft. 15 The rudder is free to rise without lifting the loose collar 45, but if the collar 45 is elevated it will cooperate with the fixed collar 44 to lift the rudder. A long operating shaft 46 is provided with forks 47 (Figs. II and IV), 20 having slotted ends adapted to receive pins on the loose collars 45. An operating handle 48 is provided with a latch rod 49 adapted to interlock with teeth on a quadrant 50. This operating handle is fixed to the shaft 25 46, to which the forks 47 are secured, and since these forks are secured to the loose collars 45, it will be readily understood that the operating handle may be actuated to simultaneously adjust all of the rudders. 30 By locating the inlet doors 6 and the inlet passageway C entirely at the front of the tunnels, I enable the tunnel walls 3 and 3' to be rigidly braced and permanently secured in fixed positions. This is quite important, 35 for the tunnel walls must withstand the lateral pressure of the streams of water discharged from the propellers, and if these walls should be displaced they would not properly engage the adjustable deflector wings 14, which are closely fitted to said walls. The means for bracing the tunnel walls 3 and 3' includes transverse braces 51, whereby the lower margins of all of these 40 walls are rigidly connected together. The braces 51 lie below the tunnel walls, and one of them is located near the rear ends of the tunnels, while the others lie near the propellers at the intake ends of the tunnels.

Cylindrical shells, preferably consisting of 50 semicircular sections 52 and 52', are arranged around the propellers, said shells being located between and secured to the longitudinal walls of the tunnels, as shown in Figs. III and X. These shells prevent lateral 55 displacement of the water at the propellers, so the several streams are forcibly discharged rearwardly from the propellers and through the open bottom tunnels. The water at the propellers can not escape by 60 passing downwardly, and when the deflector wings 14 are elevated, the forcible streams discharged rearwardly in horizontal lines will not be dissipated by the escape of water at the open bottoms of the tunnels. As a 65 further step to avoid power losses by lateral

displacement of the streams of water, abutments 53 (Figs. II and XI) extend downwardly from the longitudinal margins of each deflector wing 14 to receive the current of water discharged from the shell around 70 the adjacent propeller. These abutments are located in the upper corners of the propeller tunnels, and they have curved abutment faces conforming approximately to the curved upper portions of the shells 75 around the propellers.

The longitudinal abutments 53 brace the deflector wings 14, and the cylindrical shells 52-52' (Fig. X) serve as braces for the longitudinal walls of the tunnels. Diagonal 80 braces 54 (Fig. X) connect the semicircular shell members 52 to one of the transverse braces 51, which lies directly below the shells. These diagonal braces extend from the shell members 52 to the corners formed 85 at the junctions of brace 51 and the tunnel walls.

The suction chambers 38, located over the propellers, are secured to the shell members 52'. The forward edges of the tunnel walls 90 3-3' (Fig. III) are beveled as shown at 55 so as to offer very little resistance to the incoming water. By beveling these edges I provide relatively large intakes through which the water will flow freely into the 95 tunnels.

The use of an elevated overhanging false stern A' with propeller tunnels below the same, enables me to form the propeller tunnels at a relatively high elevation, and it is 100 not necessary for the tunnel structure to extend below the level of the bottom of the boat. This is quite desirable for a boat intended to be used in shallow water. The transverse intake passageway C (Figs. II 105 and III) can be conveniently formed between the forward ends of the tunnels and the stern A. When the intake doors 6 are open, the water will freely enter this large intake, and the power transmitted to the 110 propellers will be effectively transmitted to the streams of water confined in the tunnels. All of the tunnels are in free communication with the transverse intake, so the main stream entering the large intake is divided 115 into a number of smaller forcible streams, and the combined widths of these forcible streams may be approximately equal to the width of the boat. A very powerful boat for either deep or shallow water can therefore 120 be made by the use of the series of tunnels under the false stern.

I claim:

1. A boat having a hull provided with a stern, an overhanging false stern extending 125 rearwardly therefrom, a series of longitudinal partitions rigidly fixed to the bottom of said overhanging false stern and extending downwardly therefrom to provide a series of open bottom tunnels under the entire 130

bottom of said overhanging false stern, propellers in the forward ends of said tunnels located adjacent to the first mentioned stern, the forward ends of said partitions being separated from the first mentioned stern to provide a transverse inlet passageway, communicating with all of said tunnels, adjustable doors at the sides of the boat adapted to open and close the ends of said transverse inlet passageway, inclined deflector wings extending downwardly from the forward ends of said tunnels to the rear ends thereof, so as to form inclined top walls for said tunnels, the longitudinal edges of said deflector wings being closely fitted to the rigidly fixed partitions, pivots securing the upper ends of said deflector wings, and means for adjusting said wings.

2. A boat provided with a hull having elongated side wall members extending downwardly from its rear end, longitudinal partitions arranged between said side wall members to form a series of open bottom propeller tunnels under said rear end, propellers in the forward ends of said tunnels, said elongated side wall members and longitudinal partitions being rigidly fixed to the hull of the boat, inclined deflector wings forming the top walls of said propeller tunnels, the upper ends of said inclined deflector wings being pivoted at the forward ends of the tunnels, the longitudinal edges of each deflector wing at the side of the hull being closely fitted to the side wall member and longitudinal partition between which they are confined, the intermediate deflector wings being closely fitted to the longitudinal partitions between which they are confined, means for raising and lowering said deflector wings on their pivots, and means whereby water is admitted from the sides of the hull to the forward ends of all of said tunnels.

3. A boat having a longitudinal propeller tunnel, said tunnel being formed under the bottom of the boat, a propeller whereby water is forced through said tunnel, a cylindrical shell arranged around said propeller to confine the water discharged therefrom, an inclined deflector wing arranged at the rear of said shell to form the top wall of said tunnel, and abutments extending downwardly from the longitudinal margins of said deflector wing to receive the current of water discharged from said cylindrical shell.

4. A boat having a longitudinal propeller tunnel, said tunnel being formed under the bottom of the boat, a propeller whereby

water is forced through said tunnel, a cylindrical shell arranged around said propeller to confine the water discharged therefrom, an inclined deflector wing arranged at the rear of said shell to form the top wall of said tunnel, and abutments extending downwardly from the longitudinal margins of said deflector wing to receive the current of water discharged from said cylindrical shell, said abutments being located in the upper corners of said propeller tunnels and provided with curved abutment faces conforming approximately to the upper portion of said cylindrical shell.

5. A boat provided with a hull having elongated side wall members extending downwardly from its rear end, longitudinal partitions arranged between said side wall members to form a series of open bottom propeller tunnels under said rear end, a propeller in the forward end of each of said tunnels, a cylindrical shell arranged around each of said propellers to confine the water discharged therefrom, a suction chamber associated with each propeller tunnel, the lower end of said suction chamber being open and communicating with one of said cylindrical shells to provide for the admission of a column of water, the open lower end of said suction chamber being directly over the propeller, and means whereby water is admitted from the sides of the boat to the forward ends of all of said tunnels.

6. A boat having a longitudinal propeller tunnel, said tunnel being formed under the bottom of the boat, a propeller whereby water is forced through said tunnel, a cylindrical shell arranged around said propeller to confine the water discharged therefrom, a suction chamber having an open lower end which communicates with said cylindrical shell to provide for the admission of a column of water, the open lower end of said suction chamber being located directly over the propeller, an inclined deflector wing arranged at the rear of said shell to form the top wall of said tunnel, and abutments extending downwardly from the longitudinal margins of said deflector wing to receive the current of water discharged from said cylindrical shell, said abutments being located in the upper corners of said propeller tunnels and provided with curved abutment faces conforming approximately to the upper portion of said cylindrical shell.

In testimony that I claim the foregoing I hereunto affix my signature:

WILLIAM H. GOLDSON.
